UNITED STATES PATENT OFFICE

145,360

DESIGN FOR A COSMETIC CUP

Claudia Martucci, San Francisco, Calif.

Application August 23, 1945, Serial No. 121,589

Term of patent 14 years

(Cl. D44—9)

To all whom it may concern:

Be it known that I, Claudia Martucci, a citizen of the United States, residing in the city and county of San Francisco and State of California, have invented a new, original, and ornamental design for a Cosmetic Cup, of which the following is a specification, reference being made to the accompanying drawing, forming a part thereof.

I claim:

The ornamental design for a cosmetic cup, substantially as shown and described.

CLAUDIA MARTUCCI.
